CLAIM

The ornamental design for a medical apparatus as shown and described.

DESCRIPTION

FIG. 1 is a left front top perspective view of our new design for a fluid transfer device illustrated with an illuminated portion, and in illuminable portion in an unilluminated state; FIG. 2 is a front elevation view thereof; FIG. 3 is a rear elevation view thereof; FIG. 4 is a right side view thereof; FIG. 5 is a left side view thereof, also illustrating the illuminated portion, and the illuminable portion in the unilluminated state; FIG. 6 is a top view thereof; FIG. 7 is a bottom view thereof; FIG. 8 is a left rear bottom perspective view thereof, also illustrating the illuminated portion, and the illuminable portion in the unilluminated state; FIG. 9 is an enlarged portion of the left side view of FIG. 5, also illustrating the illuminated portion; FIG. 10 is an enlarged left side view of FIG. 5, also illustrating the illuminable portion in the unilluminated state; FIG. 11 is an enlarged left side view of FIG. 5, illustrated with the illuminable portion in a first illuminated state; and,

(Continued)

FIG. 12 is an enlarged left side view of FIG. 5, illustrated with the illuminable portion in a second illuminated state. The stippling shown in FIGS. 1, 5, 8, and 9 represents the illuminated portion of the medical apparatus. The dash-dot lines in the figures represent unclaimed boundaries of the claimed design. The dash-dot lines in the figures represent portions of the medical apparatus that form no part of the claimed design.

The surface hatching in FIG. 11 illustrates the illuminable portion illuminated in the first illuminated state. The surface hatching in FIG. 12 illustrates the illuminable portion illuminated in the second state.
